UNITED STATES PATENT OFFICE.

CHARLES H. MILLER, OF ALBANY, NEW YORK, ASSIGNOR, BY MESNE ASSIGNMENTS, TO CONSOLIDATED CAR-HEATING COMPANY, INC., OF ALBANY, NEW YORK, A CORPORATION OF NEW YORK.

HEAT DEFLECTOR.

Application filed March 11, 1926. Serial No. 93,996.

For a detailed description of the present form of my invention, reference may be had to the following specification and to the accompanying drawing forming a part thereof, wherein

5 Figs. 1 and 2 show in end view the reversed positions of the deflector;

Fig. 3 is a plan of the deflector in position;

10 Fig. 4 shows it detached and

Fig. 5 shows one of the operating cams.

My invention relates to a car seat having a heating radiator secured beneath it with a reversible heat-shield or deflector, the same 15 being an improvement on a device of that general nature shown in the patent of F. W. Butt, No. 948,309, dated February 8, 1910.

Referring to the drawings, A and B are two rock-shafts extending longitudinally beneath the seat above the heater E and journaled in any suitable manner at their ends. C and D are the usual reversing links for the seat back and in this case are fixed to the respective shafts A and B so as to rotate 20 them when shifted from one to the other of the two reversed positions shown in Figs. 1 and 2. F is the deflector of sheet metal centrally pivoted above heater E at each end in stationary brackets f, f, and formed with an angular extension along each longitudinal edge one of which extensions comes into a substantially horizontal position when the deflector is reversed. On each of the shafts A and B is a cam G split to 25 embrace the shaft and be clamped thereto by a bolt. Each cam has a curved end that bears on a flat spring H extending transversely across the top of the deflector from opposite sides, as shown in Fig. 4, and fastened thereto at one end but free at the opposite end. The cams G, G, being fast 30 on the respective shafts, are each revolved thereby slightly more than 180 degrees as those shafts are rotated by the reversal of 35 the seat backs. Thus the cams occupy alternately the positions shown in Figs. 1 and 2 and act alternately by pressure on their respective springs H, H to elevate the rear edge and depress the front edge of deflector 40 F, as shown in the same figures. The front cam in each case bears strongly on the resilient free end of its spring H, while the rear cam is out of action but forms a stop 45 for the deflector. By this simple means the

deflector F is positively reversed and locked 55 and in either position is held by spring pressure from shifting or rattling.

The purpose of the deflector is to guide the heat rising from the heater so as to protect the seat and its occupant and to divert 60 it diagonally upward and then backward towards the seat in the rear. This function of the deflector is aided by the angular extensions of the deflector, one or the other of said extensions extending downwardly 65 from the deflector in front of the heater and the other extension being spaced upwardly from the heater and lying in an approximately horizontal position.

What I claim as new and desire to secure 70 by Letters Patent is:

1. A heat deflector for a car seat mounted above the heater and below the seat and provided with a reversing connection to the back of the seat including a spring secured 75 to the deflector, and means movable into engagement with said spring to yieldingly hold the deflector in its reversed position.

2. A heat deflector for a car seat mounted above the heater and below the seat and 80 provided with a reversing connection to the back of the seat including rock-shafts, cams on said shafts, and operating links between said shafts and the back of the seat.

3. A heat deflector for a car seat mounted above the heater and below the seat and provided with a reversing connection to the back of the seat including rock-shafts, cams on said shafts bearing on springs secured 85 to the back of the deflector and operating 90 links for said shafts worked by the back of the seat.

4. A heat deflector for a car seat pivotally and centrally mounted above the heater and below the seat with operating cams therefor, one on each side of the pivotal axis, and operating connections between each of 95 said cams and the back of the seat.

5. A heat deflector for a car seat pivotally and centrally mounted above the heater and 100 below the seat, with two parallel rock-shafts operated by the back of the seat in reversing, two cams, one on each of the respective rock-shafts and free-ended springs on the said deflector on which the said cams respectively bear.

6. A heat deflector for a car seat comprising a flat body the longitudinal edges of

which are provided with downwardly and outwardly inclined extensions, means by which said deflector may be movably mounted above a heater and below the seat and maintained in an inclined position, a reversing spring connected to the deflector, and means movable into engagement with said spring to yieldingly hold the deflector in its reversed positions, so that in either of

(10) the inclined positions of said body one of

said extensions will closely overhang the heater and the other extension will be elevated to a horizontal position to allow free escape of any heat which may accumulate beneath said body.

15

Signed at Albany, county of Albany, State of New York, this 8th day of March, 1926.

CHARLES H. MILLER.
